US00D878862S

(12) **United States Design Patent** (10) **Patent No.:** **US D878,862 S**
(45) **Date of Patent:** **** Mar. 24, 2020**

(54) **BLENDING SYSTEM**

(71) Applicant: **Vita-Mix Management Corporation**,
Olmsted Township, OH (US)

(72) Inventors: **Phonesacksih Guy Kettavong**, Kent,
OH (US); **Jack Warren Gee, II**,
Willoughby, OH (US); **Kolman Juhasz**,
Parma, OH (US); **Eugene J.
Kozlowski**, Medina, OH (US); **David
A. Kanning**, Valley City, OH (US);
Michael Patrick Arnett, Columbia
Station, OH (US); **Richard Joseph
Lash**, Avon Lake, OH (US)

(73) Assignee: **Vita-Mix Management Corporation**,
Olmsted Township, OH (US)

(**) Term: **15 Years**

(21) Appl. No.: **29/682,508**

(22) Filed: **Mar. 6, 2019**

CLAIM

The ornamental design of a blending system, as shown and described.

DESCRIPTION

FIG. 1 is a perspective view of a portion of a blending system showing our new design;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The broken lines in the figures are included for the purpose of illustrating portions of a blending system and form no part of the claimed design.
